(57) **CLAIM**

The ornamental design for a tire as shown and described herein.

DESCRIPTION

FIG. 1 is a perspective view of a tire showing my new design, it being understood that the pattern is repeated uniformly throughout the circumference of the tread.

FIG. 2 is a front elevational view thereof. The top and bottom views are identical.

FIG. 3 is a rear elevational view thereof.

FIG. 4 is a left side view thereof.

FIG. 5 is a right side view thereof; and,

FIG. 6 is an enlarged fragmentary view from upper 6-6 to lower 6-6 of FIG. 2.

The broken lines illustrate environmental subject matter only and themselves form no part of the claimed design. The dash-dot-dash lines indicate a boundary of the claimed design and are not themselves part of the claimed design. The surface shading lines and stippling in the drawings depict the character or contour of the surfaces represented and do not by themselves form part of the claimed design.
